CYLINDRICAL PAPER STOCK SCREEN

Hervey G. Cram, Appleton, Wis., assignor to Combined Locks Paper Company, Combined Locks, Wis., a corporation

Filed Mar. 17, 1958, Ser. No. 722,624

7 Claims. (Cl. 209—273)

This invention appertains to the art of paper making and more particularly to the screening of paper stock, pulp and the like.

One of the primary objects of my invention is to provide means for continuously screening paper stock by the use of a novel cylindrical screen constructed and arranged in such a manner that a compact and durable structure will be had and so that the screen itself will not be effected by wear incident to the passage of fibers therethrough.

It has been proposed to utilize a cylindrical screen formed from a metal shell having a plurality of spaced perforations or slots of a selected size therein. The continuous passage of the stock with the suspended fibers therein soon causes wear on the walls of the openings or slots, resulting in the enlargement of the openings or slots. This necessitates the frequent changing of the screens with consequent cost and loss of time in the shutting down of the apparatus.

It is, therefore, another salient object of my invention to provide a cylindrical screen having a continuous spiral slot therein terminating unobstructed at its discharge end, so that a continuous flow of acceptable stock therethrough from one end of the screen to the other is insured without appreciable wear thereon.

A further object of my invention is to provide a cylindrical screen formed from a continuously wound spiral band having a width greater than its thickness with the convolutions of the band equidistantly spaced throughout the screen, the width of the band insuring longevity of the screen incident to any wear thereon.

A further important object of the invention is to provide an axially pivoted spiral blade disposed within a screen having a continuous spiral slot to bring about a required rotational minimum non-contact relation with the screen for insuring the correct flow of stock through the entire length of the screen and to cause the desired flow of acceptable stock through the screen, the spiral blade being of such a construction as to cause a pulsation of stock through the screen and thus insure the proper cleaning thereof at all times, the blade also functioning to assist in the movement of the rejected material toward the discharge end of the apparatus.

A still further object of the invention is to provide means for the control of the rotational speed of the spiral blade so that the time required for the passage of unscreened stock to pass from one end of the screen to the other can be accurately governed according to the quality of the stock, i.e., the amount of accepted stock passing through the screening section, and/or, the amount of acceptable stock passing along with the rejected material.

A still further important object of the invention is to provide a hollow cylindrical body mounted within the cylindrical screen and carrying the spiral blade, whereby the interior area of the screen will be materially reduced so as to provide a comparatively thin mass of unscreened stock in contact with the spiral screen and thus effect a

2

maximum screening efficiency with relation to the screening section area.

Another important object of my invention is to provide means for utilizing the hollow body to permit the desired dilution of the stock entering the screen, the arrangement being such as to deliver the dilution water axially through the body to be discharged to the unscreened stock at a required point or points for the effective separation of the acceptable stock passable through the screen from the unacceptable material impassable through the screen.

Another further important object of my invention is the novel arrangement of the inlet of the stock relative to the spiral blade, whereby the incoming stock will impinge upon the blade and thus tend to turn the freely rotatable blade so that any power required for rotating the blade will be reduced to a minimum.

With these and other objects in view, the invention consists in the novel construction, arrangement and formation of parts, as will be hereinafter more specifically described and claimed, and illustrated in the accompanying drawings, in which drawings,

Figure 1 is a longitudinal sectional view through my novel screening machine;

Figure 2 is a fragmentary transverse sectional view taken through the improved machine on the line 2—2 of Figure 1, looking in the direction of the arrows, the view being on a greater scale than Figure 1;

Figure 3 is an enlarged fragmentary detail transverse sectional view through the screen itself illustrating the manner of mounting the spiral screen body on its supporting bars;

Figure 4 is a fragmentary longitudinal sectional view through the screen taken on the line 4—4 of Figure 3, looking in the direction of the arrows, and

Figure 5 is an enlarged fragmentary side elevational view of the screen body with its supporting bars removed to more clearly show the continuous spiral slot.

Referring to the drawings in detail, wherein similar reference characters designate corresponding parts throughout the several views, the letter M generally indicates the screening machine and the same includes a supporting frame 10 of any preferred character. The frame can include a base plate 11 having mounted thereon a frame body 12 to which is welded, or otherwise secured, transversely extending spaced bracket plates 13. At one end of the body 12 is fixed a supporting column 14 to which is firmly secured the base of the drive motor 15. The drive motor 15 is provided with a variable speed control 16 of a well known character. The purpose of the motor 15 and its speed control 16 will later appear.

Extending longitudinally of the frame 10 is a cylindrical casing 17 and the same is firmly supported by the bracket plates 13. Welded to the outer surface of the cylindrical casing 17 at its terminals are fastening rings 18 and these rings are adapted to abut against the casing heads 19 and 20. It is to be noted that the inner faces of the casing heads 19 and 20 are shouldered, as at 21, to receive and support the casing. Bolts 22 are utilized to fasten the securing rings 18 to the casing heads 19 and 20 and certain of these bolts can be utilized to connect the casing with the bracket plates 13.

Secured to the casing head 19 is the hollow inlet head 23 for unscreened stock and secured to the casing head 20 is a hollow head 24 for rejected material. Communicating with the head 23 is a supply pipe 25 for unscreened stock and this pipe can lead from any suitable source of supply. The head 24 has communicating therewith a depending pipe 26 for rejected material. The casing 17, itself, carries an outlet pipe 27 for accepted stock.

The casing 17 has mounted axially therein the longitudinally extending screening section 28 which divides the casing into an outer chamber 29 for accepted stock and an inner chamber 30 for unscreened stock. The screening section 28 forms an important feature of this invention and it is to be noted that the same extends from one end of the casing to the other. The screening section 28 is provided with a spiral slot 31 which extends from one end of the screen to the other, and thus from one end of the casing to the other. To form the cylindrical screen section 28 with its spiral slot, a relatively thin metal band 32 is spirally wound and it is to be noted that the width of the band is greater than its thickness. The band is firmly held by supporting bars 33 which extend longitudinally of the screen and these bars are equidistantly spaced around the periphery of the screen. The ends of the bars are received in notches 34 formed in the inner edges of annular plates 35 fitted within the casing 17. The inner edges of the supporting bars 33 carry longitudinally extending rubber or like resilient strips 36 and the spirally wound band 32 embeds itself in the resilient strips and these strips 36 effectively hold the convolutions of the band at their desired equidistantly spaced relationship throughout the entire length of the screen.

Rotatably mounted within the screening section 28 is the hollow dilution body 37. This body is in the nature of a cylinder and the same extends beyond the opposite ends of the screen. Firmly affixed to the ends of the dilution body 37 are end collars 38 and 39. Secured to the collar 38 is a drive shaft 40 and this shaft is connected by a coupling 41 to the armature or output shaft 42 of the motor 15. The collar 39 has firmly secured thereto a pipe 43 for dilution water (white water). The shaft 40 and the pipe 43 are rotatably mounted in suitable supporting bearings 44 and 45 carried by the inlet head 23 and the dilution head 24. The pipe 43 leads to a slip joint 46 and this joint has connected therewith the pipe 47 for the dilution water. Flow of the dilution water 47 into the dilution body 37 is controlled by a valve 48 disposed in the length of the pipe 47.

Carried by and rotatable with the dilution body 37 is a spiral blade 49 and the outer edge of the blade is disposed in close proximity to, but slightly spaced from, the inner surface of the screening section 28. The outer edge of this blade has its inner surface beveled, as at 50, for a purpose, which will now appear.

The dilution body 37 is of a definite size in relation to the interior diameter of the screen section 28 so that the interior area of the screening section will be materially reduced. This only permits a comparatively thin mass of unscreened stock to pass along the interior of the screening section 28 to bring about a maximum screening efficiency with relation to the screening section area.

The dilution body 37, itself, is provided with a slot 51 so as to permit the flow of dilution water from the dilution body into the unscreened stock chamber 30. The dilution water enters axially through the dilution body 37 and this dilution water is discharged into the unscreened stock at a required point for the effective separation of the acceptable stock and the rejected stock.

At this point, it is to be noted that the speed of rotation of the dilution body 37 and its spiral blade 49 is effectively controlled by the speed of the motor 15. This is important, as obviously, the speed of rotation of the spiral blade is governed according to the quality of the stock being supplied to the machine. It is also to be noted, that the travel of the unscreened stock along the screening section 28 is in a spiral direction as guided by the spiral blade 49. Hence, the lead of the spiral blade 49 also determines the length, and/or, time of contacting of the stock with the cylindrical screening section 28 in passing from the intake to the discharge of the screen.

As an example, of the passage of the stock through the machine, the following is given.

With the spiral blade 49 in a fixed stationary position, and, with a screening section diameter of 12 inches and a length of twenty inches, and the spiral blade having a lead of three inches, the unscreened stock would travel: $24/3 \times 3.1416$, or approximately 25 feet in passing from end to end of the screen. However, in order to be effective in clearing the screening section, i.e., continually moving the rejected material along the screening section for discharge at the end, it is essential that the spiral runner be in rotation, and, the speed of its rotation directly affects:

- 15 (1) The time allowed for contact with the screening section in passing.
- (2) The length (spiral) of screen contact in passing.
- (3) The rate of flow through the screen.
- (4) The direction angle of the unscreened stock with the screening section slot in passing.

Therefore, based on a fixed pressure delivery to the screen, the cleanliness of the rejected material, or in other words, freeness of acceptable material therein is directly relative to the rotational speed of the spiral runner blade, and, is the reason for the provision of the adjustable speed control requirement as previously mentioned.

While I have illustrated the invention as applied to a cylindrical screen, it is to be understood that the principles of my invention are equally applicable to flat or conical disc screens. In disc type screens the strip is spirally wound from the center to the periphery and the continuous slot is thus formed.

Changes in details may be made without departing from the spirit or the scope of this invention, but what I claim as new is:

1. In a machine for screening paper stock and the like, a cylindrical casing having an inlet at one end for unscreened stock and an outlet at its other end for rejected stock, a stationary cylindrical screen in said casing dividing the casing into an interior chamber for unscreened stock and an outer chamber for acceptable stock, said inner chamber communicating at one end with the inlet for unscreened stock and with the outlet for rejected stock at its other end, said casing having an outlet communicating with the outer chamber for acceptable stock, and a longitudinally extending hollow dilution body disposed within said cylindrical screen and disposed axially thereof, means for supplying dilution water to the body, and said body having an outlet for dilution water intermediate its ends.
2. In a machine for screening paper stock and the like as defined in claim 1, and said dilution body having a diameter less than the interior diameter of the cylindrical screen but in close relation thereto, whereby unscreened stock will pass between the dilution chamber and the cylindrical screen in a thin mass.
3. In a machine for screening paper stock and the like as defined in claim 2, and means between the dilution body and the cylindrical screen for forcing the thin mass of material in a spiral path past the screen.
4. In a machine for screening paper stock and the like as defined in claim 2, and a spiral blade carried by the outer surface of the dilution body terminating adjacent the inner surface of said cylindrical screen and spaced slightly therefrom.
5. In a machine for screening paper stock as defined in claim 3, means for rotatably supporting the dilution body, and a spiral blade carried by the outer surface of the dilution body extending substantially from one end of the screen to the other.
6. In a machine for screening paper stock and the like as defined in claim 3, and said cylindrical screen having a continuous spiral slot extending from one end thereof to the other, means rotatably supporting the dilution body in the cylindrical screen, and a spiral blade

5

carried by the outer surface of the dilution body extending substantially the full length of the screen.

7. In a machine for screening paper stock and the like as defined in claim 6, and said spiral blade having its outer edge beveled in the direction of the outlet for rejected stock.
